UNITED STATES PATENT OFFICE

HAROLD LEVY, OF NEW YORK, N. Y.

NOTE HOLDER AND DISPENSER

Application filed October 20, 1926. Serial No. 142,837.

This invention relates to an improved note holder and dispenser employed for counting currency or for holding bank notes, checks, bills, and the like, either of uniform or varying sizes, and to generally facilitate the counting and dispensing thereof.

Among the objects of the invention are to provide a novel and simple construction for the purpose stated which will greatly facilitate manufacture and particularly the assembly of the device; to provide novel means for firmly holding the currency or notes, as well as to prevent injury or tearing thereof when being placed in position or removed; to facilitate the individual removal of the notes while firmly retaining the remainder of the notes in position and holding them flat; to accommodate notes of different lengths and, generally to provide a device for use by tellers or other persons handling such paper, which is also adapted to be accommodated within money drawers or cash registers, and to generally improve and enhance the value of devices to which the invention relates.

Another object of the invention is to adapt the device to cash-drawers per se or as used in connection with cash registers and to enable the device to project above the top of the drawer automatically when the drawer is open and to be lowered as the drawer is pushed in or closed, thus facilitating the making of change by permitting more convenient access to notes or bills.

Other objects and advantages will be apparent as the description proceeds.

In the drawings:—

Figure 1 is a plan view of my novel note-holder and dispenser.

Fig. 2 is a front elevation partly broken away and in section of the device shown in Figure 1.

Fig. 3 is a side or end elevation of the device shown in Figs. 1 and 2.

Fig. 4 is a sectional view, taken on the line 4—4 of Figure 6, showing a modified structure adapted especially for cash-drawers and shown in a lowered position with the drawer closed or pushed in.

Fig. 5 is a view similar to Figure 4 but showing the device in the position which it

assumes when the drawer is opened or pulled out.

Fig. 6 is a plan view showing the device in the cash-drawer.

Figs. 7 and 8 are transverse vertical sectional views taken on the section lines 7—7 and 8—8 of Figure 4.

Fig. 9 is a plan view of another modification especially adapted for table or desk use, and

Fig. 10 is a vertical longitudinal sectional view taken on the section line 10—10 of Figure 9.

Referring to the drawings in detail, in which like reference characters designate corresponding parts throughout the several views, 4 designates the table or base of the device, which may be of metal or wood and is of such size that it may be accommodated within the compartment of a cash-drawer. 65 However, this is not essential since the device may be arranged upon a bench or desk in convenient position for use without placing the same in a cash-drawer or compartment of the cash register. Arranged upon the base 4 and suitably bolted or otherwise fastened thereto are a series of spaced uprights consisting of corner members 5 having their upper ends formed with integral and downwardly projecting portions or hook-like members 6 extending toward each other in opposite directions with respect to the uprights of each pair at each end of the base. The uprights 5 form guides for a plate 7, suitably apertured as indicated at 8, to freely slide up 75 and down thereon and guided thereby in its movements. This plate is normally held in an upward position under spring tension or pressure as by means of suitable springs such as helical and substantially frustro-conical coil springs 9, which are arranged around the uprights 5 and rest upon the base 4, or are inserted between the base and the plate 7 so as to exert upward pressure against the latter and force the same toward the extremities of the bent or hook-shaped portions 6 or against the engaging ends thereof.

Another pair of similar uprights 10 are arranged on the base 4 intermediately of its rear side or edge, and it will be noted that 100

the front and rear sides or edges of the base 4 project beyond the front and rear sides or edges of the plate 7, as clearly shown in Figures 1 and 3 of the drawings, so as to give a steady support for the device and also to accommodate the uprights 10 outwardly of the rear side or edge of the plate 7. The upper ends of the uprights 10 are also bent forwardly and downwardly to provide hook-shaped portions 11, the lower ends of which extend over the plate 7 and, like the forward uprights 5, receive suitable engaging members which may be in the form of flexible rubber cups or suction members 12, although the essential character of these members is to provide a large engaging head to contact with the papers and prevent tearing or mutilation thereof, in addition to firmly retaining the papers in position. In the preferred form, the engaging faces of these members 12 are concaved to give a slight grip or suction action, but other suitable engaging members may be provided in lieu thereof. While the outer rear uprights 5 may be provided with similar members, it is preferred to provide them with cups 13, preferably of some hard material such as metal or composition, to receive bearing balls 14 in the cups or sockets thereof, which will not only hold the notes but will permit the same to be readily removed, as in withdrawing a sheet of paper from the pile, without in any way tearing or otherwise injuring the note. Of course, it is to be understood that the stack of notes, designated at 15 in the drawings, is firmly retained in position and kept compact and flat, but that when they are removed a slight pressure is exerted upon the stack against the action of the springs 9 to slightly depress the plate 7, as indicated in dotted lines in Fig. 2 of the drawings, thus permitting the currency, note, or bill to be easily removed. It will also be apparent that the notes or checks may be of different lengths and of any width accommodated between the opposed pairs of the uprights 5 at the front and rear sides of the device.

An important advantage of the invention is the facility with which the notes or papers may be handled, owing to the fact that by depressing the plate 7, the notes may be readily inserted beneath the engaging portions of the uprights at the lower ends of the curved portions thereof and also by reason of the fact that the front of the device between the uprights 5 and the engaging members thereof is freely open and unobstructed by any holding means or guides, thereby permitting the notes to be quickly and easily removed without tearing or other objections. It has also been found in practice that when the notes are inserted, either in the form of bank notes, checks, bills, or the like, that they will automatically become straightened or flattened out, and in this way will be main-

tained in perfect condition, as well as prevented from being blown about or disarranged as compared with the systematic way in which they are held by the construction described.

In the use of the device with the bills or notes held therein, the user places the four fingers of one hand on the bills between the engaging members at the front, suitable space being left therebetween to readily accommodate the fingers. With slight pressure to release the tension of the springs or other suitable means used for retaining the pack tight and holding the ends in place, the note is shifted forwardly to slide the uppermost note from the pile and the thumb will then be passed under the same. The enlarged heads or engaging members on the curved ends of the uprights will properly hold the notes in position when the springs are acting, but will permit the same to be easily displaced when the device is operated as just described.

The uprights 5 and 10 and plate 7 form a guide frame for the notes to permit convenient placing or insertion therein from above with slight bending, crumpling, or collapsing at the ends of the notes to dispose them below the engaging members 12, 13, and 14. Owing to the guide frame being substantially freely open at one side or at the front between the uprights 5, as distinguished from the ends, the notes or bills can be easily removed individually at this side upon slight depression on the pile or pack, to facilitate counting and dispensing. Also, by such depression the stack or pile can be easily removed at either end, due to the fact that the ends are freely open and unobstructed between the uprights 5 or guide frame formed thereby.

In the form of the device shown in Figures 4 to 8 inclusive, a structure is shown which is especially adapted for use in connection with cash-drawers per se or of cash registers. In this instance the part of the cash register or cabinet which receives the drawer and forms a guide therefor is designated at 16, the same having a bottom wall, a rear wall 17, and a top wall 18 which is provided with a rearwardly facing shoulder or fixed obstruction 19 in the roof or top thereof, as in connection with most, if not all cash registers. The open front of this cabinet is adapted to receive a drawer 20 and this drawer has a coin or money receptacle 21 and a note or bill compartment 22, over the rear portion of which is provided a wall 23, leaving the remainder of the top portion of the compartment open. These compartments or partitions in most cash-drawers are about the same length as a bill and, therefore, with any device below the level of the partition, it is almost impossible to remove the bills. My construction or device is such that it will be automatically raised above the level of the drawer—that is, the top thereof—when the drawer is opened so as to

permit convenient access to the bills. This device comprises a base 24 which is set in the bottom of the compartment 22 and substantially fits the same. A supplementary base 25 is mounted on the base 24 and is shorter than the latter so that its rear side edge terminates slightly in front of or adjacent to the front side or edge of the wall 23, at which point the rear end of the supplementary base 25 is hinged to the base 24, as indicated at 26, in such a manner that the part 25 can swing angularly up and down or toward and away from the part 24. The part 25 may be guided in its movements by an upright member 27 anchored to the base 24 and received in a slot 28 in the front side or edge of the auxiliary base 25 and having a rearwardly directed upper end 29 forming a stop to limit the upward movement of the part 25 under the action of an expansion spring 30, which is attached to the bottom thereof. This spring is preferably a leaf spring anchored intermediate as at 31 to the part 25, one being provided at each side so as to project the holder above the top of the drawer when it is opened as shown in Figure 5, while the spring flattens out and permits the holder to be disposed below the top of the drawer by engagement with the roof of the drawer compartment when the drawer is closed.

In the construction of the holder the upright guides 32 are formed of six flat strips of metal or other suitable material, three on each side, having inturned ends anchored to the supplementary base 25 as indicated at 33, the intermediate fastening means serving as mountings for springs 34 at each side. However, it is to be understood that any desired number of said guides 32 may be employed. These springs are also leaf springs and may be either double or single, or one may be mounted one above the other in reverse positions. A plate 35 is mounted to slide in the uprights or guides 32 and may be recessed as indicated at 36 along its side edges for this purpose, thereby preventing the plate 35 from becoming displaced. This plate may also be recessed at the top as indicated at 37 to take a pad or cushion 38 of felt, rubber, or other suitable material. It also will be noted that the plate 35 is shorter than the bottom plate or base 24 and approximately of the same length of the supplementary plate or base 25 so that it will be accommodated in front of the top wall 23 and the bill partition of the cash-drawer at its front portion with the bills or notes 39 projecting rearwardly thereof. In lieu of the arrangement shown in Figure 1, the four enlarged bearing members at the ends are preferably in the form of ball bearings 40 corresponding to the members 14, being composed of cups in which the balls are mounted to exert pressure without friction, and the two intermediate members are in the form of cups 41 constituting

enlarged engaging members or heads carried by the uprights or guides 32 at their inwardly directed upper ends, so as to be arranged over the bills or notes. It should also be noted that one side of the device is open, but this open side is located at the front of the drawer and the device or at one end of the latter instead of at one long side, so that there are three guide members at each side and the bills are accessible at the front end or side.

It will be noted that in Figure 5 the springs 30 project the bills above the top of the drawer when the latter is pulled out, and in order to guide the device below the drawer when the latter is pushed in, as shown in Figure 4, spring strips 42 are mounted in each side on the inwardly directed upper ends of the forward guides 32, as indicated at 43. The springs are fixed at this end and have their opposite ends slotted longitudinally as indicated at 44 to slide beneath headed pins or retainers 45 as they are longitudinally distended or as they flex in the positions shown in Figures 4 and 5, respectively. Thus, as the drawer is pushed in, the upwardly curved intermediate portions of the springs 42 will strike the top of the drawer compartment and be compressed so as to flatten the springs 30 and lower the device into the drawer compartment 22. When the drawer is pulled out the springs 42 strike the fixed obstruction or shoulder 19 while riding along the top roof or wall 18. In this way the device is retained in a lowered position until the drawer is pulled out, when it will be automatically raised by the springs 30 owing to the pressure on the springs 42 being removed. It will thus be seen that the device shown in Figures 4 to 8 inclusive will be automatically lowered and moved into the drawer compartment when the drawer is closed and will automatically rise above the top of the drawer when the latter is opened, permitting more convenient access to the bills.

In Figures 9 and 10 of the drawings the construction is similar to that shown in Figures 4 to 8 inclusive except that this device is adapted for desk or table use and has a somewhat enlarged and thickened fanciful base 25' and instead of having a single upright or guide 32 between the end upright guides at both sides, two guides 32' are provided at one side to take the cups or enlarged engaging heads 41', and one long side is left open as in connection with the form shown in Figure 1 of the drawings. The springs 34 are each anchored as at 33'. In Figures 1 and 9, it will be noted that the uprights or guides are omitted at one long side, while one short side is open in the form shown in Figure 6, leaving a freely open and unobstructed side, that is, an end or front portion to permit access to and free removal of the notes or bills upon depressing the same

against the action of the springs in the manner heretofore described.

While I have shown and described my invention in a preferred form, I am aware that various changes and modifications may be made without departing from the principles of my invention, the scope of which is to be determined by reference to the appended claims.

I claim as my invention:

1. In a note holder, a guide frame, a spring-pressed member on the frame guided thereby and normally held upwardly, engaging members on the frame having depending portions opposing the spring-pressed member and adapted to hold a stack of notes between the spring-pressed member and depending portions in flattened-out position, said frame being freely open between at least two depending portions to accommodate a hand in depressing the notes for removal of the same.
2. In a note holder, a guide frame, a spring-pressed plate on the frame guided thereby and normally held upwardly, upright engaging members on the frame having depending engaging heads opposing the spring-pressed plate and adapted to hold a stack of notes between the plate and heads in flattened-out position, said frame being freely open between certain of said members with sufficient space to permit withdrawal of the notes therebetween.
3. In a note holder, a guide frame having relatively short and long sides, a spring-pressed member on the frame guided thereby and normally held upwardly, engaging members on the frame near each end of the long sides thereof opposing the spring-pressed member and adapted to hold a stack of notes therebetween in flattened-out position, and an intermediate engaging member on at least one long side, all of said members having engaging heads beneath which the notes are disposed.
4. In a note holder and dispenser, a base, uprights mounted on the base, a plate slidably mounted on the uprights for movement toward and away from the base, expandible resilient members between the base and the plate, and enlarged engaging heads facing downwardly from the upper ends of the uprights.
5. In a note holder and dispenser, a base, uprights on the base including end uprights and other uprights between at least two of the end uprights, a plate slidably mounted on certain of said uprights to receive a stack of notes thereon, springs adjacent said uprights between the base and plate, said uprights having their upper ends bent over the plate, and depending note-engaging members on said ends.
6. In a note holder and dispenser, a guide frame arranged to accommodate a stack of unfolded currency notes or the like, means to

support the frame, means to cause the frame to swing upwardly at the front, and means to cause the frame to swing downwardly when the device is positioned in the bill compartment of a cash-drawer and the latter is closed.

7. In a note holder, a guide frame adapted to be received in a cash drawer, a spring-pressed member on the frame guided thereby and normally held upwardly, engaging members on the frame opposing the spring-pressed member and adapted to hold a stack of notes therebetween in flattened-out position, said frame being hinged at its rear end to swing upwardly at the front, spring means to normally raise the frame, and means at the top of the frame to cause depression thereof into said cash-drawer by engagement with the top wall of the drawer compartment upon the drawer being closed.

8. In a note or bill holder and dispenser for cash-drawers, a guide frame adapted to be mounted in the drawer to swing upwardly at the front of the drawer, means to normally raise the frame, a normally elevated support guided in the frame and adapted to mount the bills thereon, engaging members carried by the frame and disposed in contact with the bills at the top, and engaging members at the top of the frame adapted to contact with the roof of the drawer compartment and depress the holder into the drawer when the drawer is closed.

9. In a note holder and dispenser, a base, uprights mounted on the base, a plate slidably mounted on the uprights for movement toward and away from the base, expandible resilient members between the base and the plate, and engaging heads extending downwardly from the upper ends of the uprights to engage the notes or the like.

10. In a note or bill holder and dispenser for cash drawers, a guide frame adapted to be mounted for tilting movement in a compartment of a cash drawer, means for normally tilting said frame upwardly, means on the frame to engage the top of the compartment of the cash drawer for depressing the frame when the drawer is pushed in, uprights on the frame, springs on the frame, a plate guided by said frame and supported on the springs and engaging members carried by the uprights and extending downwardly therefrom to contact with notes or bills resting on the plate.

11. In a note holder and dispenser, a base, confining means mounted on the base, a plate slidably mounted between said confining means for movement toward and away from the base, expandible resilient members between the base and the plate, and inwardly extending overhanging portions having engaging members extending downwardly from the top of the confining means and extending inwardly to engage the notes or the like while permitting said notes to be readi-

ly inserted in position or withdrawn through the space provided therebetween.

12. In a note or bill holder and dispenser, the combination with a cash drawer having a roof, a guide frame mounted in the drawer to swing upwardly at the front, means to normally raise the frame, a support guided in the frame and adapted to receive the bills thereon, means to raise the support and adapting the same to be depressed, engaging means carried by the frame and disposed in contact with the bills at the top, and engaging means on the frame adapted to contact with the roof of the drawer to depress the holder into the drawer when closed.

13. In a note holder and dispenser, a base, confining means carried on the base, a plate slidably mounted between said confining means for movement toward and away from the base, and inwardly extending overhanging portions with anti-friction engaging members extending downwardly from the top of the confining means to engage the notes for holding the same and permitting the notes to be grasped for removal between certain of the engaging members.

14. In a holder and dispenser of the class described, a base, confining means mounted on the base and having inwardly extending overhanging portions, a plate held between the confining means for movement toward and away from the base, expansible means between the base and plate normally elevating the plate, engaging members carried by the overhanging portions to contact with the notes or the like, and anti-friction members on certain of said engaging members to facilitate withdrawal of the notes.

15. In a note holder and dispenser, a base, confining means carried on the base, a plate slidably mounted between said confining means for movement toward and away from the base, and inwardly extending portions with engaging members at the top of the confining means to engage the notes for holding the same and permitting the notes to be grasped for removal between certain of the engaging members.

16. In a note holder and dispenser, a frame arranged to accommodate a pile of notes in a compartment and including means to grip and hold the pile of notes independently of the compartment and to permit free removal of the notes individually from the front, means to hingedly support said frame at its rear end and remote from the front of the compartment, means to cause the frame to tilt upwardly at the front and means to guide the frame in its tilting movements.

17. In a note holder and dispenser, a frame arranged to accommodate a pile of notes in a compartment and including means to grip and hold the pile of notes and permit free removal of the same individually, means to pivotally support said frame at its rear end

and permit the same to swing upwardly at the front above the top of the compartment, means to cause the frame to tilt upwardly at the front, and means adapted to be engaged and depressed to cause the frame to swing downwardly into the compartment when closed.
